UNITED STATES PATENT OFFICE.

JOHN ANTHONY SMITH, OF SPOKANE, WASHINGTON.

CALCULATOR.

Application filed December 3, 1923. Serial No. 678,297.

To all whom it may concern:

Be it known that I, JOHN A. SMITH, a citizen of the United States, residing at Spokane, in the county of Spokane and State of Washington, have invented certain new and useful Improvements in Calculators, of which the following is a specification.

This invention relates to calculators of the type disclosed in Letters Patent, No. 10 1,422,944, granted to H. S. Edmondson, July 18, 1922. One object of the present invention is to provide a cover which may be manipulated to serve as a stand or support for the calculator when it is in use, and another 15 object of the invention is to provide a construction whereby the several parts of the calculator may be stamped from sheet metal so that the completed device will be light, compact and durable. A still further object 20 of the invention is to provide a construction whereby the several parts of the calculator may be rapidly assembled and, when assembled, held in compact operative relation without employing any permanent securing 25 means, and yet another object of the invention is to provide means whereby the number strips may be all returned to zero position after use by a single movement of a setting element. Other objects of the invention 30 will appear incidentally in the course of the following description.

In the accompanying drawings:

Figure 1 is a front elevation of the improved calculator arranged for use;

Fig. 2 is a side elevation of the same;

Fig. 3 is a longitudinal section on the line 3—3 of Fig. 1, the device being arranged to be carried in a pocket;

Fig. 4 is a transverse section on the line 40 4—4 of Fig. 1;

Fig. 5 is a detail section with parts in plan taken upon the line 5—5 of Fig. 4;

Fig. 6 is a detail section on the line 6—6 of Fig. 5;

Fig. 7 is an edge view showing the device arranged for use in the hand;

Fig. 8 is a plan view of the guide plate;

Fig. 9 is an edge view of one of the number strips, and

Fig. 10 is a detail view of the clearing bar.

In carrying out my present invention, I employ a face plate 1 which is provided in its lower portion with a central longitudinal slot 2 enlarged at its lower end for a purpose which will presently appear, the

sides of the slot being defined by ribs 160 struck up from the face plate, as best shown in Fig. 4. Above the said central longitudinal slot 2, the face plate is provided with a transverse series of longitudinal slots 3 through which a pencil or pointed instrument is to be inserted to manipulate the proper strips in the manner set forth in detail in the patent to Edmondson hereinbefore mentioned, while above the said transverse series of longitudinal slots the face plate is provided with a transverse row of openings 4 through which the digits upon the number strips may be read to note the result of an addition or subtraction. The face plate is provided at all its edges with the rearwardly extending walls 5 whereby a housing is provided for the number strips and the parts supporting the same. The edge portions of the side and bottom walls 5 are turned laterally outward to form flanges 6. The top wall 5 is merged into a depending lip or flange 7 which constitutes a partial back wall, as shown clearly in Fig. 3. A guide plate 8 is employed, and this guide plate is of proper dimensions to fit closely but easily within the side and end walls of the face plate and between the main body of the face plate and the lip or flange 7, as shown clearly in Fig. 3. The side edges of this guide plate are struck up, as indicated at 9, to form flanges which, by bearing against the inner surface of the face plate 1, will serve to properly space the two plates 10 and provide a chamber in which the number strips 10 may easily slide. The guide plate 8 is also provided on its upper face with beads or ribs 11 forming between them channels or grooves in which the number strips 10 may slide and by which they will be guided, as will be readily understood upon reference to Figs. 5 and 6. These guiding ribs may be conveniently formed by striking up a portion of the guide plate, as clearly shown in Fig. 6. The guiding ribs will extend to points adjacent the ends of the slots 3 in the face plate and will also extend from points above the upper ends of said slots to points near the upper end of the face plate so that they will offer no obstruction to the lateral movement of the manipulating tool in the operations of addition and subtraction but at the same time will be sufficiently extensive to provide complete operative guides for the number strips. The said number strips are provided with notches 12 in their side

edges to be engaged by a manipulating tool as set forth fully in the above mentioned patent and the upper portions of the strips are finished in a color contrasting with the 5 color of their lower portions for the purpose particularly set forth in said patent. To aid in reading the results attained by the use of the calculator, the surface of the face plate adjacent the several slots 3 is given different 10 colors so that the tens and units may be readily distinguished from the hundreds, and the hundreds readily distinguished from the thousands. Reversely arranged series of figures, indicated at 13, are also displayed upon 15 the face plate adjacent each slot 3 to be referred to when any particular operation of addition or subtraction is to be performed, it being understood that my present calculator is operated in exactly the same manner 20 as the calculator disclosed in the aforesaid patent. The number strips are bowed longitudinally, as shown in Fig. 9, whereby they will frictionally engage the opposed surfaces of the face plate and the guide plate 25 with sufficient tension to remain in any position in which they may be set. A small teat 14 is struck up from each strip adjacent its lower end, and these several teats are adapted to bear against the inner surface of the 30 face plate between the several slots 3 therein so that the area of contact with the face plate will be reduced and liability of the strips to defacement overcome. A setting or clearing bar or strip 15 is provided, and 35 this setting bar or strip is placed upon the guide plate 8 between the same and the face plate and is guided at one end by the adjacent flange 9 and at its opposite end by a rib 90 struck up from the guide plate and 40 alined with the corresponding rib 11, as shown in Figs. 5 and 8. This clearing bar is provided between its ends with an up-standing knob or handle element 16. This knob or handle member is preferably struck 45 up from the bar and may be of any approved form, although in the present drawings I have shown it as substantially T-shaped, having a head which is adapted to be passed upwardly through the widened lower end 17 50 of the guide slot 2, and a shank which is adapted to enter and play in the slot 2 upon upward movement of the evener or setting bar with the head projecting over the sides of the said slot and resting upon the ribs 55 160, as clearly shown in Fig. 4. The head is provided with a notch 161 in that edge of its shank which is presented to the number strips so as to accommodate the web 162 in the face plate between the slot 2 and the 60 alined slot 3, thereby permitting the edge of the bar to project under said web and push the number strips fully home to the zero position. In assembling the parts, the number strips are simply placed upon the 65 upper surface of the guide and supporting plate 8 between the ribs 11 without especial care being observed to place them at the upper end of the plate, it being only necessary to see that the numbered portions of the strips are at the upper ends thereof. The 70 clearing or setting bar 15 is also placed upon the guide plate with its knob disposed substantially on the central longitudinal line of the plate, after which operation the upper end of the guide plate is engaged between 75 the lip or flange 7 and the body of the face plate, and then pressed toward the face plate so that the knob 16 will pass through the widened lower end 17 of the guide slot 2. The evener bar is then pushed upwardly 80 along the slot 2 and will thus be brought into contact with the lower ends of all the number strips and will push the same upwardly until their movement is arrested by the contact of their upper ends with the top wall of the face plate. When the strips have been thus positioned, the nought or zero digit upon the strips will appear at the respective openings 4 in the face plate. To retain the guiding and supporting plate 85 90 within the chamber provided by the face plate and its walls, I provide a back plate 18 which is formed at one end and both side edges with reentrant flanges 19 adapted to engage around the flanges 6 of the face plate and slide upon the same so that the back plate will be readily and effectually assembled with the face plate and will serve as an efficient means for retaining the guiding and supporting plate 8 in place. The back plate 95 100 is of less length than the face plate and the guiding and supporting plate so that the upper end of the back plate will, when the parts are assembled, be spaced from the back lip 7, while the lower end of the back plate will have its flange 19 engaged with the bottom flange 6 of the face plate, the extent to which the back plate may be pushed toward the top of the face plate being thus limited. 105 110

The parts so far described constitute a complete operative calculator, the number strips of which may be manipulated by the insertion of a pencil point through the proper slots 3 to engage notches 12 in the respective number strips. I provide, however, a stylus 20 which may be engaged through an eye or sleeve 21 formed upon one edge of the back plate so that a suitable manipulating tool will be at hand whenever the 115 use of the device is desired. 120

To further protect the parts from injury when the device is not in use, I provide a cover consisting of front and back plates 22 and 23 preferably covered with leather which is extended between the adjacent edges of said plates, as indicated at 24, to constitute a hinge. The back plate is preferably divided transversely near one end so that the leather covering will form a hinge or 125 130

fold, as shown at 25, and to the end section of the back plate, I secure a retaining plate 26 which is adapted to engage between the backing plate 18 and the guiding and supporting plate 8 and fits snugly therebetween so that it will serve to hold the guiding plate and the number strips resting thereon firmly against the face plate whereby the parts will be maintained in proper operative relation 5

10 at all times. The end of the retaining plate 26 is adapted to abut the edge of the back lip 7 so that, when the cover has once been assembled with the other parts, it cannot be accidentally removed, although it may be 15 easily withdrawn when necessary by merely springing the free end of the back 23 slightly away from the said back lip 7. The free ends of the front and back leaves or members of the cover are provided with stud and 20 socket fastening members 27 whereby the cover may be held in closed position, as shown in Fig. 3, when the device is to be carried in a garment pocket. When the device is to be used, the front leaf of the cover 25 may be swung into a horizontal position, as shown in Fig. 2, with the lower end of the back plate 18 resting against the fastening member 27, whereupon the said leaf 22 will constitute a base and support for the device, 30 while the leaf 23 will constitute a brace and the fastening member 27 will serve as a stop to prevent collapse of the device as thus set up. This arrangement is clearly shown in Fig. 2 of the drawings and brings the calculator into a position where it may be very 35 easily and conveniently manipulated by the user. The front leaf 22 may, however, be merely folded over the back leaf, as shown in Fig. 7, so that the device may be held in 40 the hand in the same manner as a writing tablet.

From the foregoing description, taken in connection with the accompanying drawings, it will be seen that I have provided a construction whereby the several parts may be very easily assembled and, when assembled, will be brought into such compact and close relation that no extraneous fastening devices are needed and the parts will be effectually held against accidental separation. The construction, however, is such that, if, through some accident or other cause, an element should be broken or so badly bent or otherwise damaged as to render the use of

the device uncertain or impractical, the parts 55 may be easily disassembled to permit such repairs as may be necessary or the substitution of a new part for the damaged part. The construction devised by me facilitates the shaping of the several elements in stamping presses so that the device may be produced very economically and placed upon the market in a very durable form. 60

Having thus described the invention, I claim: 65

1. In a calculator, the combination of a face plate, a guide plate supported below the face plate, and a plurality of bowed number strips slidably mounted upon the guide plate between the same and the face plate and provided at their lower ends with projections bearing against the under surface of the face plate. 70 -

2. In a calculator, the combination of a face plate having marginal top, bottom and side walls projecting rearwardly therefrom and a back lip depending from its top wall parallel with the face plate, a guide plate having one end engaged between the said back lip and the face plate and abutting the top wall of the face plate, the said guide plate fitting closely within the walls of the face plate and provided along its side edges with flanges bearing at their outer sides against said walls and at their edges against 85 the under surface of the face plate, a back plate carried by the bottom and side walls of the face plate, means abutting the back lip and resting on the back plate for holding the said guide plate to the face plate, and a 90 plurality of number strips slidably mounted upon the said guide plate between the same and the face plate.

3. In a calculator, the combination of a face plate having openings therethrough, a 95 guide plate disposed below the face plate and having longitudinal guide ribs struck up therefrom, said ribs bearing against the under surface of the face plate, number strips slidably supported on the guide plate 100 between said ribs, a back plate engaged marginally with the face plate, and a cover having a member engaged between the back plate and the guide plate and holding the guide plate to the face plate. 105

In testimony whereof I affix my signature.

JOHN ANTHONY SMITH. [L. S.]
